EMERGENCY LIGHT OR TORCH NO. 1

Charles Linhardt, Jr., Baltimore, Md.

Application February 6, 1937, Serial No. 124,451

1 Claim. (Cl. 48—35)

My invention relates to certain new and useful improvements in a gas emergency light or torch No. 1, efficient to operate, and one that can be manufactured and sold at a comparatively low 5 cost.

A further object of my invention is the provision of an emergency light or torch which may be conveniently and safely stored without any material deterioration and one which may be 10 quickly put in operative position and in which the light will burn for a considerable length of time after the light has been ignited.

A further object of this invention is the provision of an emergency light or torch provided 15 with a porous tube on its interior which will prevent the mushy detritus of spent carbide from clogging or choking the water entrance to the casing.

A still further object of the invention is the 20 provision of an emergency light or torch having a gas making chamber, a water conveying entrance into said chamber and a means surrounding the water entrance to prevent said entrance from becoming clogged by the spent carbides contained within the casing.

With these and other objects in view, the 25 invention consists in certain novel features, combination and arrangement of parts as will be hereinafter more fully described, pointed out in 30 the accompanying drawing, and claimed.

In the drawing,

Figure 1 is a side elevational outside view of 35 my improved emergency light or torch, as made in accordance with this invention;

Figure 2 is a top plan view of the same;

Figure 3 is a transverse sectional view, taken on 40 the line 3—3 of Figure 2; and,

Figure 4 is an inverted or bottom plan view of 45 the invention.

Referring to the drawing, the numeral 5 indicates a casing and is preferably formed of a cylindrical shell of metal or like material suitable for the purpose, having a bottom portion 6 and a top portion 7, all soldered or welded together to 50 form a unitary water tight receptacle, as clearly illustrated in Figure 1.

To maintain the casing in a buoyant upright position, I provide the bottom portion 6 with an annular weight member 8 and I locate the same 55 centrally of said bottom portion so as to assure a vertical position of the casing at all times when in water.

The bottom portion 6 is provided centrally with an opening 9, through which water is adapted to 55 pass when the device is submerged, and surround-

ing this opening 9 on the interior of the bottom portion 6 is a perforated supporting boss 10. This boss 10 has secured thereto, the lower end of a perforated tube 11 and its free end extends upwardly into the casing 5 terminating adjacent 5 the central portion thereof. The extreme upper end of the perforated tube 11 is folded back upon itself, as at 12, to constitute a closure therefor.

The purpose of this tube is to permit the water entering the opening 9 to pass up through the 10 perforations of the boss 10 into and out through the tube 11 into the casing 5, and there the water will mingle with suitable carbide "A", which has been previously placed in the casing 5 about the tube 11.

Secured over the opening 9 in the bottom portion 6 and closing the same is a removal tab 13, which has one end free constituting a handle 14. This tab is secured to the bottom 6 over the opening 9 so as to form a normal air and water tight 20 seal until it is stripped therefrom by grasping the handle portion 14 and tearing it from the bottom portion 6. This action is accomplished prior to placing the casing in water and by virtue of removing this tab 13 water is permitted to 25 enter opening 9, perforations of the boss 10 through tube 11 into the carbide "A", which immediately generates gas that travels towards the top 7.

The carbide "A" is placed in sufficient quantity 30 in the casing 5 so as to leave a gas chamber 15 between the carbide "A" and top 7, as clearly illustrated in Figure 1.

The top member 7 is provided centrally with 35 perforations 16, constituting gas escapement openings and they are preferably closed by a removable cap 17 removably sealed thereto in a normal air and water tight condition. The cap 17 is provided in one end with a removing ring 18, which permits this cap to be torn quickly 40 from the top 7 when the device is placed in use.

Secured to the inner side of the top and about 45 the openings 16 is a baffle 19, which is for the purpose of preventing the flames from backfiring into the gas chamber 15, specific details of construction will be more fully described in my co-pending application executed and filed as of even date herewith.

The operation of the device is approximately 50 as follows—when it is desired to use the emergency light or torch, it is only necessary to remove the tab 13 and cap 17 by tearing them from their respective top and bottom of the casing 5, placing the casing in a container of water and by virtue of the water it will immediately 55

assume an upright position and water passing through opening 9 and openings of the tube 11 will mingle with the carbide "A" and the gas generating therefrom will slowly rise to chamber 15, passing through screen 13 and openings 16, where it is ignited and by virtue of this a continuous flame will be ignited for a considerable length of time at a comparatively small cost.

It is also to be understood that the approximate pressure of the gas in chamber 15 will be between five and seven pounds and when it reaches the maximum point the flow of water through the opening 9 will cease until such pressure in the chamber 15 decreases below a point equivalent to five pounds, at which time the pressure is relieved and new gases generated, as previously described.

It is also to be understood that the self-igniting structure illustrated and claimed in my two previous patents, No. 1,445,222, February 13, 1923, and No. 1,737,424, November 26, 1929, can be used in this type of casing and light, if found desirable.

While I have described one embodiment of the invention in the preferred form, it will be obvious

that various changes might be made in the construction, combination and arrangement of parts which could be used without departing from the spirit of my invention and I do not mean to limit the invention to such details except as particularly pointed out in the claim. 5

Having thus described my invention, what I claim as new is:

An emergency light comprising a casing, a top and bottom hermetically sealing the ends of said casing, said bottom provided with an opening, a perforated boss surrounding said opening on the interior of said bottom, a perforated tube having one end closed and its free end secured to and surrounding said boss, said tube terminating into 15 and adjacent the central portion of said casing so as to prevent the spent carbide from clogging or choking said water openings in the boss and bottom of the casing, said top provided with an outlet gas opening, and means to close the gas 20 and water openings of the top and bottom, respectively.

CHARLES LINHARDT, JR.
